CLAIM

The ornamental design of a tear open bottle cap, substantially as shown.

DESCRIPTION

FIG. 1 is a top front perspective view of a tear open bottle cap showing my new design;

FIG. 2 is a left side elevational view thereof; the right side being a mirror image thereof;

FIG. 3 is a rear elevational view thereof;

FIG. 4 is a bottom plan view thereof;

FIG. 5 is a top front perspective view of a second embodiment of a tear open bottle cap, showing my new design;

FIG. 6 is a left side elevational view thereof;

FIG. 7 is a rear elevational view thereof; and

FIG. 8 is a bottom plan view thereof.

*Fig. 1**Fig. 2**Fig. 3**Fig. 4**Fig. 5**Fig. 6**Fig. 7**Fig. 8*
